UNITED STATES PATENT OFFICE.

TEDDIE C. VANDEBERG, OF EPPING, NORTH DAKOTA.

COMPOUND HAND AIR-COMPRESSING PUMP.

Application filed February 19, 1923. Serial No. 619,837.

To all whom it may concern:

Be it known that I, TEDDIE C. VANDEBERG, a citizen of the United States, residing at Epping, in the county of Williams and State of North Dakota, have invented certain new and useful Improvements in Compound Hand Air-Compressing Pumps, of which the following is a specification, reference being had to the accompanying drawings.

This invention relates to compound hand air compressing pumps and has for its primary object to provide an improved pump of this kind particularly adapted for use in connection with the inflation of vehicle tires.

The present invention is adapted, however, for general use, and is especially adapted for use wherein a maximum of compression is required to be produced in a minimum of space, with a minimum weight and number of parts.

With the above general objects in view, and others that will become apparent as the nature of the invention is better understood, the same consists in the novel form, combination and arrangement of parts herein-after more fully described, shown in the accompanying drawings and claimed.

In the drawings, wherein like reference characters designate corresponding parts throughout the several views:—

Figure 1 is a longitudinal vertical section of an air compressing pump embodying the improvements of my invention;

Figure 2 is a horizontal sectional view on the line 2—2 of Figure 1; and

Figure 3 is a detailed sectional view of the check valve employed.

Referring more in detail to the drawings, the present invention embodies a relatively large low compression cylinder 1 and a relatively small high compression cylinder 2. The cylinders 1 and 2 are detachably mounted at their lower ends upon an elongated cast metal base 3 which has upstanding circular flanges 3^a into which the lower ends of the cylinders 1 and 2 are detachably threaded, the opposite ends of the base plate 3 projecting a suitable distance so that the operator may place his feet thereon for steadyng the pump in the usual manner.

A piston rod 4 is provided for the high compression cylinder 2 while a similar piston rod 4^a is provided for the low compression cylinder 1, the rods 4 and 4^a being

rigidly connected at their upper ends by means of a cross bar 5 whose projecting ends are formed to provide handles 5^a to be gripped by the operator for reciprocating the pistons P and P' of the low compression and high compression cylinders respectively. The piston rods 4 and 4^a are of similar lengths so that the pistons P and P' are simultaneously positioned in the same horizontal plane, the piston P being provided with a downwardly facing packing cup, while the piston P' is provided with an upwardly facing packing cup. This enables compression of air below the piston P and above the piston P'.

The upper end of the high compression cylinder 2 is provided with a removable screw threaded cap 6 having a central opening through which the rod 4 works, said cap 6 being provided with a suitable packing gland 7 so as to prevent leakage of air from the cylinder 2 around the rod 4. The upper end of the low compression cylinder 1 is provided with a similar removable screw threaded cap 8 whose central portion is provided with an aperture which requires no packing in view of the fact that air is not compressed above the piston P. In order to brace the cylinders 1 and 2 against separating strains which would produce leakage at the connection of the cylinders with the flanges 3^a, a brace plate 9 is suitably secured at one end to the cap 8 and is detachably secured as at 9^a to the cap 6 so that these caps may be independently removed or applied for ready assembling of the device or repair after use.

The lower end of the low compression cylinder 1 is provided with an opening communicating with an opening through the flange 3^a of said cylinder 1, and a suitable inlet check valve 13 connected with the opening of said flange 3^a for permitting air to enter the cylinder 1 beneath the piston P while preventing the escape of such air through the valve 13 upon the downward compression stroke of the piston P. The flange 3^a of the cylinder 1 is provided with a port at its side near the cylinder 2 and its port communicates with the lower end of a pipe 11 which extends upwardly between the cylinders and has its upper end in communication with the interior of the high compression cylinder 2 at the upper end of the latter. A check valve 12 is arranged in the pipe 11 so as to permit free passage of

the air from the cylinder 1 to the cylinder 2, while preventing return of such air from cylinder 2 to cylinder 1.

The cast base 3 is provided with a curved 5 passage affording communication between the lower ends of the cylinders 1 and 2 as at 15 and the upper end of the high compression cylinder 2, and its cap 6 is provided with an outlet port communicating with a 10 suitable outlet hose 10 which may be provided with means upon its outer free end, in the usual manner, for connection with the valve of a pneumatic tire.

From the foregoing it will be readily seen 15 that the present pump is exceedingly simple in construction, requiring only two check valves and packing for only the piston of the high compression cylinder.

In operation, on the up stroke of the pistons P and P' air is drawn into the lower ends of both cylinders through the check valve 13 and the port or piston 15, at the same time such air as is within the high compression cylinder 2 being forced out of 25 the same through the hose 10, while the loose fit of the piston rod 4 in the cap 8 will allow relief of pressure from above the piston P. On the down stroke of the piston, the air passes and is forced by piston P from 30 the low compression cylinder 1 through pipe 11 past the check valve 12 into the upper end of the high compression cylinder 2. On the next up stroke of the pistons the previously 35 compressed air which has been delivered from cylinder 1 to the cylinder 2 is forced out through the hose 10, through the tire, both cylinders again drawing in air through the check valve 10 and piston 15, as above mentioned. This provides a powerful 40 and simple pump having only one connecting rod or piston rod that requires packing, therefore providing an easy working pump for obtaining high pressure through manual operation.

45 It is believed that the construction and operation as well as the advantages of the present invention will be readily understood and appreciated by those skilled in the art.

50 Minor changes may be made without departing from the spirit and scope of the invention as claimed.

What is claimed is:—

55 1. A compound hand air compressing pump comprising a relatively large low compression cylinder, a relatively small high compression cylinder, a piston within the low compression cylinder constructed to have effective compressing action only upon downward movement thereof, a piston within the high compression cylinder constructed to have effective compression action only upon the upward stroke thereof, a base provided with upstanding circular flanges in which the lower ends of said cylinders are removably secured, an air intake check

valve communicating with the lower end of the low compression cylinder, said base having a passage forming direct communication between the lower ends of both cylinders, a removable cap for the low compression cylinder having a central opening, a piston rod loosely passing through the opening of the cap of the low compression cylinder and carrying the piston of the last named cylinder upon its lower end, a removable cap for the high compression cylinder having a central opening surrounded by a packing gland, a piston rod having a working fit in the gland of the last named cap and having the piston of the high compression cylinder fixed on the lower end thereof, a handle rigidly connecting the upper ends of the piston rods above the cylinders with the pistons of both cylinders positioned in the same horizontal plane, a pipe providing communication between the interior of the low compression cylinder at the lower end of the latter and the high compression cylinder at the upper end of the latter, said pipe being arranged between the cylinders and having a check valve therein permitting free flow of air from the low compression cylinder to the high compression cylinder and preventing return of air from the high compression cylinder to the low compression cylinder, said high compression cylinder having a compressed air outlet in its upper end.

2. A compound hand air compressing pump comprising a relatively large low compression cylinder, a relatively small high compression cylinder, a piston within the low compression cylinder constructed to have effective compressing action only upon downward movement thereof, a piston within the high compression cylinder constructed to have effective compression action only upon the upward stroke thereof, a base provided with upstanding circular flanges in which the lower ends of said cylinders are removably secured, an air intake check valve communicating with the lower end of the low compression cylinder, said base having a passage forming direct communication between the lower ends of both cylinders, a removable cap for the low compression cylinder having a central opening, a piston rod loosely passing through the opening of the cap of the low compression cylinder and carrying the piston of the last named cylinder upon its lower end, a removable cap for the high compression cylinder having a central opening surrounded by a packing gland, a piston rod having a working fit in the gland of the last named cap and having the piston of the high compression cylinder fixed on the lower end thereof, a handle rigidly connecting the upper ends of the piston rods above the cylinders with the pistons of both cylinders positioned in the same horizontal plane, a pipe providing communication be-

tween the interior of the low compression cylinder at the lower end of the latter and the high compression cylinder at the upper end of the latter, said pipe being arranged 5 between the cylinders and having a check valve therein permitting free flow of air from the low compression cylinder to the high compression cylinder and preventing return of air from the high compression cylinder to the low compression cylinder, said

high compression cylinder having a compressed air outlet in its upper end, and a brace connecting the upper ends of the cylinder including a plate fixed to the cap of one cylinder and detachably secured to the 15 cap of the outer cylinder whereby said caps may be independently removed.

In testimony whereof I hereunto affix my signature.

TEDDIE C. VANDEBERG.
